Primary Examiner — Sandra Snapp(74) Attorney, Agent, or Firm — Mashburn Law Office, LLC; Donna Denise Mashburn(57) CLAIM

The ornamental design for a sofa, as shown and described.

DESCRIPTION

FIG. 1 is a side perspective view of the sofa;
 FIG. 2 is a front perspective view of the sofa; and,
 FIG. 3 is a back perspective view of the sofa.
 The broken lines in FIGS. 1-3 are directed to environment and are for illustrative purposes only. The broken lines form no part of the claimed design.
